FIG. 1 is a perspective environmental view of a shake siding panel having a lower edge and having a contoured front face simulating natural wood. Adjacent panels, shown in phantom, illustrate an environment for the shake siding panel and form no part of the claimed invention. An upper interlock is also shown in phantom and forms no part of the claimed invention.

FIG. 2 is a front view of the shake siding panel.

FIG. 3 is a side view of the shake siding panel illustrating the contoured lower edge slanting inwardly from the front face and upwardly towards a lower interlocking lip.

FIG. 4 is a top view of the shake siding panel shown in FIG. 2.

FIG. 5 is a bottom view of the shake siding panel with the contoured lower edge; and,

FIG. 6 is a rear view of the shake siding panel with the contoured lower edge extending below the lower interlocking lip.
